UNITED STATES PATENT OFFICE

102,748

DESIGN FOR A SPOON

Sofia Erikson, Foster Center, R. I.

Application May 11, 1936, Serial No. 62,602

Term of patent 7 years

To all whom it may concern:

Be it known that I, Sofia Erikson, a citizen of the United States, residing at Foster Center, in the county of Providence and State of Rhode Island, have invented a new, original, and ornamental Design for a Spoon, of which the following is a specification, reference being had to the accompanying drawing, forming part thereof.

I claim:—

The ornamental design for a spoon, as shown.

SOFIA ERIKSON.
